ELECTRIC SNAP-SWITCH.

1,262,331.

Specification of Letters Patent.

Patented Apr. 9, 1918.

Application filed November 20, 1916. Serial No. 132,250.

To all whom it may concern:

Be it known that I, MONROE GUETT, a citizen of the United States, residing at Hartford, in the county of Hartford and State 5 of Connecticut, have invented certain new and useful Improvements in Electric Snap-Switches, of which the following is a specification.

This invention relates to electric snap switches, the object of the invention being 10 the provision of an article of this character which is exceedingly simple in construction, which is susceptible of inexpensive manufacture and ready assemblage of its 15 parts, and which is effective and accurate in operation. The improvements are capable of advantageous incorporation in switches of various types.

In the drawings accompanying and forming 20 part of the present specification I show in detail one convenient form of embodiment of the invention which will be set forth fully in the following description. I do not restrict myself to this showing; I may depart 25 therefrom in several respects within the scope of the invention defined by the claims following said description. In this particular representation, the invention is shown as comprising part of a pendent switch, 30 wherein it operates in a satisfactory manner. As may be inferred, however, I do not limit myself to this particular use.

Referring to said drawings:

Figure 1 is a top plan view with the upper 35 section of the casing removed.

Fig. 2 is a vertical sectional view of the switch.

Fig. 3 is a horizontal section on the line 3-3 of Fig. 2, looking in the direction of 40 the arrow.

Fig. 4 is a plan view of an actuator.

Fig. 5 is a detail view of an arm.

Fig. 6 is a detail view in elevation of a pin.

Fig. 7 is a detail view in elevation of an anti-friction roller.

Like characters refer to like parts throughout the several views.

As has been observed, I do not limit myself 50 to the employment of the invention in any particular form of switch, although it possesses utility when used in conjunction with or forming part of a pendent snap switch as illustrated partly in Figs. 1, 2 and 3.

55 There is a support. This support may be

of any desirable nature; as shown it consists of a body 2 of some suitable insulating material as porcelain or composition. The several parts of the snap movement and certain adjunctive elements are in the case 60 of a pendent snap switch, inclosed by a suitable casing such as that denoted in a general way by 3 and which may consist of two sections united by a screw-thread or other convenient joint, the lower or main section 65 of the metal casing 3 receiving the insulating body 2 and the upper having an opening which receives a bushing as 4 for the passage of the suspending cord, the wires of which are adapted to be electrically and 70 mechanically associated with wire connecting members as will hereinafter more particularly appear.

The device involves a suitable actuator such as that denoted in a general way by 5 75 in Figs. 1 and 2 and which is illustrated in detail in Fig. 4. This actuator comprises the buttons 6 and 7 of insulating material molded onto or otherwise connected with the terminal portions of the intermediate 80 metallic body 8, these buttons being accessible exteriorly of the casing 3 as shown in both Figs. 1 and 2. Said actuator has an endwise reciprocative movement in a straight path in the construction shown, although this may not always be necessary, for as may be inferred, I do not necessarily confine myself to any particular details of construction. This intermediate metallic body 8 has between the buttons 6 and 7 the 85 elongated slot 9, which is widened as at 10 between the ends thereof, the widened portion of the slot being virtually of elliptical form and receiving within it in the present case, a switching member such as that denoted in a general way by 11 and herein-after described. To support and guide the actuator any suitable means may be provided, the posts or uprights 30 being shown for this purpose, these brackets being mounted 95 at opposite sides of a chamber or cavity (hereinafter described) in the upper surface of the insulating supporting body 2. The sides of the said posts or uprights 30 are notched as at 31 to slidingly receive the intermediate portion 8 of the actuator and thus guide it. Said posts or uprights may be held in fixed position in any desirable manner as by the screws 32 extending through perforations in said insulating 100

105

110

body and threaded into the feet 33 of the posts 30. The switching member comprises an arm 12 and an anti-friction roller as 13, the anti-friction roller constituting the 5 active part of the switching member. While as will be hereinafter evident, this anti-friction roller is quite advantageous as the terminal portion of the switching member, it is not always necessary that I should 10 utilize it. Obviously it travels in a comparatively frictionless manner and serves the additional function of a bridging piece. It will be clear that it is of conducting material. The arm 12 which carries this anti-friction roller or bridging member 13 is 15 of sheet metal, although this is not a vital point. The base portion 14 of the arm 12 has an aperture 15 which receives for rotation the central or reduced portion 16 of 20 the anti-friction roller. Said anti-friction roller, as will be clear, comprises two end cylindrical portions and a connecting neck of the pivot portion of reduced diameter which has a rotative connection or association 25 with the arm 12. Said arm and anti-friction roller constitute a switching member.

The upper surface of the insulating body 2 as shown is furnished with a cavity, chamber or pocket as 17, the bottom of which is on a downward arc or concaved, and although I do not imperatively require such a formation, it is of advantage. It presents a runway or guide way for the bridging member or anti-friction roller 13, the end walls 18 and 19 of the chamber or cavity presenting stops of advantageous form for the switching member when the same is in the respective positions, or when the switch 40 is respectively on and off. It is shown as off in both Figs. 1 and 2 by full lines, and as on by dotted lines in said Fig. 2. In Fig. 3 the anti-friction roller 13 acting as the operative part of the switching member 45 is shown in both positions by dotted lines.

This switching member through the arm 12 has an operating connection with the actuator 5, and I will now set forth a construction which properly meets my purposes 50 in this respect. Extending across the wide part 10 of the slot in the actuator 5 is the pin 20, the intermediate portion 8 of the actuator having bearings 21 of practically tubular form to pivotally receive the duplicate journals 22 of the pin 20, said pin between its ends having the groove 23 which receives the bifurcated portion 24 of the arm 12, said bifurcated portion straddling the pivot pin 25 which connects the enlarged 55 portions 26 of the pin 20, these enlarged portions bearing against the opposite side walls of the practically elliptical part 10 of the slot 9. This provides a construction by which endwise movement of the pin 20 is 60 prevented. The pin itself furnishes a con-

venient way of pivotally connecting the switching arm 12 with the actuator 5 therefore and provides also for the proper relative endwise movement of said arm 12. As the arm 12 is forked, it will be clear that it has 70 an open slot at its outer end.

Between the actuator 5 and the arm 12 is interposed suitable spring means by which the necessary snap movement at the proper time can be imparted to said arm. The 75 means shown for this purpose and the way it is associated with the actuator and the switch arm 12 are desirable. Around the said arm 12 is a coiled spring 27 constantly under some stress, one end of the spring 80 bearing against the under face of the intermediate portion of the actuator 5 while the other end bears against the shoulders 28 formed at the junction of the foot 14 with the body of the arm 12. This spring as 85 may be gathered, acts as a convenient means for imparting the requisite snap movement to the arm 12 or its equivalent. Set against the stop surface 18 are contacts 35 and 36 which are provided with angular shanks 90 37 under the bases of the wire connecting members 38, these bases being held in place in some suitable manner, as by the screws 39 and having means as by screws 41 for the connection with the wires therewith. As 95 will be clear, these wire connecting members 38 have electrical connection with the transverse shanks of the two contacts 35 and 36. These two contacts have upright portions which bear against the stop surface 18 and 100 are continued for a short distance along the adjacent portion of the bottom of the chamber or cavity 17. Said contacts are, of course, separated but are adapted when the switch is on to be bridged by the anti-friction roller 13, as will be hereinafter set forth.

In Fig. 1 the switching member 11 is off, the roller 13 at this time being against the stop face 19 and the bottom of the cavity 110 as shown by full lines in Fig. 2. To close the circuit or to move the switching member 11 to on, the following procedure may be adopted. The button 6 as shown by full lines in said Figs. 1 and 2 it will be perceived, extends a greater distance from the casing 3 than the button 7. This button 6 will be pushed to the right in the present case thus moving the arm 12 of the switching member to an upright position. Before 115 this upright position is reached the dead center relation is assumed, the dead center line intersecting the axes of the roller 13 and the pin 20. During this motion the spring 27 is compressed which results in its 120 being further stressed. The instant the center of connection between the pin 20 and the actuator 5 crosses this dead center line when the actuator is following the direction set forth, the stressed spring acting against the 125

shoulders 28 will snap the switching member 11 to the dotted line position in Fig. 2 which is its on position, the spring through the intermediate parts moving the actuator 5 of which the two buttons form a part to the dotted line position in said Fig. 2. The stop surface 19 holds the switching member 11 against movement until the dead center line is crossed in the manner set forth, at which time the switching member, as I have already observed, is rapidly swung over to the dotted line position, where it can abut against the stop face 18 or against the upright portions of the contacts 35 and 36 fitted against said stop surface, thus arresting the motion of the switching member. It will be clear when the switching member is arrested by this stop surface 18 or the fixed contacts 35 and 36, the anti-friction roller 13 will engage the two contacts 35 and 36 and will electrically bridge the space or interval between them. To open the circuit the actuator 5 will be moved from the dotted line to the full line position in Fig. 2, during which movement the action just described will be reversed. The bottom of the cavity 17 is advantageously convexed or on a depressed arc by which I can obtain proper control and guiding of the switching member in its on and off movements.

I have described a spring which meets my conditions in an eminently desirable manner. This spring is conditioned by being stressed. As may be inferred it is possible that this type of spring may not always be utilized.

What I claim is:

1. A switch comprising supporting means, an actuator in coöperative relation with said supporting means, a switching member having a connection with the actuator, spring means interposed between the actuator and the switching member, the support having stops engageable by the switching member 40 when in the on and the off positions thereof and also having a guide surface to be traversed by the switching member when moved between said on and off positions, said guide surface being situated between said stops, 45 and the actuator on its movements being adapted to operate the switching member and at the same time stress the spring means and the spring means when stressed acting to snap the switching member between its 50 respective positions.

2. A switch comprising supporting means, an actuator in coöperative relation with said supporting means, a switching member having a connection with the actuator, spring 55 means interposed between the actuator and the switching member, the support having stops engageable by the switching member when in the on and the off positions thereof and the actuator on its movements being 60 adapted to operate the switching member

and at the same time stress the spring means and the spring means when stressed acting to snap the switching member between its respective positions, the support having a guide surface for the passage of the operative portion of the switching member between said positions. 70

3. A switch comprising supporting means, an actuator in coöperative relation with said supporting means, a switching member having an operative connection with the actuator, spring means between the actuator and the switching member, the operative portion of the switching member being in the form of an anti-friction roller and the supporting means having a guide surface to be traveled by the anti-friction roller in moving from the on to the off positions and vice versa, said supporting means having stops to be engaged by the switching member when in the on and the off positions, and said guide surface being disposed between said stops. 75

4. A switch comprising supporting means, an actuator in coöperative relation with said supporting means, a switching member having an operative connection with the actuator, spring means between the actuator and the switching member, the operative portion of the switching member being in the form 80 of an anti-friction roller and the supporting means having a guide surface to be traveled by the anti-friction roller in moving from the on to the off positions and vice versa, said supporting means having contacts and the anti-friction roller being of conducting material and adapted to bridge the contacts when the switching member is in the on position. 85

5. A switch comprising supporting means 90 having a chamber, the bottom of which constitutes a guide surface, an actuator in coöperative relation with the supporting means and the switching member having an actuating connection with the actuator, 95 means governed by the actuator for effecting a snap movement of the switching member to on and off positions in alternation, the switching member being adapted to traverse said guide surface on the movement of the 100 switching member. 110

6. A switch comprising supporting means having a chamber, the bottom of which constitutes a guide surface, an actuator in coöperative relation with the supporting means 115 and the switching member having an actuating connection with the actuator, means governed by the actuator for effecting a snap movement of the switching member to on and off positions in alternation, the 120 switching member being adapted to traverse said guide surface on the movement of the switching member, and said guide surface being concaved. 125

7. A switch comprising supporting means 130

4

having a chamber, the bottom of which constitutes a guide surface, an actuator in co-operative relation with the supporting means, a switching member having an actuating connection with the actuator, means governed by the actuator for effecting a snap movement of the switching member to on and off positions in alternation, the switching member being adapted to traverse said guide surface on the movement of the switching member, and said guide surface being concaved, said switch having stops to arrest the switching member when in said on and off positions.

15. 8. The combination of supporting means having a concaved guide surface and also having stops approximately at opposite ends of said guide surface, an actuator in co-operative relation with the supporting means, a switching member having an operative connection with the actuator, means governed by the actuator for effecting snap movement of the switching member to on and off positions, the switching member in moving from one position to the other, traversing the said guide surface.

9. The combination of supporting means having a concaved guide surface and also having stops approximately at opposite ends of said guide surface, an actuator in co-operative relation with the supporting means, a switching member having an operative connection with the actuator, means governed by the actuator for effecting snap movement of the switching member to on and off positions, the switching member in moving from one position to the other, traversing said guide surface, and the supporting means having contacts resting against one of the stops and to be electrically bridged by the switching member when in the on position thereof.

10. The combination of supporting means, an actuator in co-operative relation with the supporting means, a switching member having a loose pivotal connection with the actuator and also having a circuit governing portion, and a spring interposed between the actuator and the switching member and conditioned by the actuator on the movement thereof, the spring being adapted when thus conditioned to impart a snap movement to the switching member when the actuator has moved a predetermined distance, said supporting means having in turn means to positively prevent the movement of the circuit governing portion of the switching member until the actuator reaches a certain point.

60. 11. A switch of the class described comprising supporting means having a walled cavity and also having contacts, an actuator on said supporting means, a switching member loosely connected with the actuator and the free end provided with means for bridg-

ing said contacts, a spring interposed between the actuator and the switching member and stressable by the actuator on opposite movements thereof, and means for preventing movement of the free end of the switching member until the spring is stressed and also until the center of connection between the switching member and the actuator has approximately crossed the dead center line, the free end of the switching member being adapted to traverse a wall of said cavity on the motion of the switching member.

12. A switch comprising an insulating body having a cavity and also provided therein with stops, an actuator supported by the body and having a pin, a forked arm straddling the pin and slotted to receive the pin, and a spring interposed between the actuator and the arm, the free end portion of the forked arm constituting a circuit controlling portion and being adapted to traverse said cavity on the motion of the forked arm by the actuator, the stops arresting the circuit controlling portion when in the on and the off positions.

13. A switch comprising an insulating body having a concaved surface and also having stops at the end of the surface, said body further having contacts, an actuator supported for straight line movement, a switching arm having a loose pivotal connection with the actuator between the ends thereof, a spring interposed between the actuator and the arm, the operative part of the arm being in the form of an anti-friction roller which constitutes an electrical bridging element for said contacts.

14. An insulating body having a concaved surface, an actuator supported and in co-operative relation with the body, a single switching arm provided with a shoulder and also with an anti-friction roller to traverse said surface, and a spring bearing against the actuator and also against the shoulder on the arm.

15. A switch comprising an insulating body having a concaved surface terminating in stops, an actuator comprising a slotted intermediate portion and also comprising buttons at the ends of the intermediate portion, the body having means for supporting said intermediate portion for straight line movement, said intermediate portion having a pin extending across the slot, a switching arm projecting into the slot and forked to receive the pin, a spring surrounding said arm and bearing against the same and also against the intermediate portion of the actuator, and an anti-friction roller to traverse said surface, the anti-friction roller having an operative connection with the arm.

16. A switch comprising supporting means, an actuator in co-operative relation with said supporting means, a switching

member having an operative association with the actuator, spring means between the actuator and the switching member, the supporting means having a fixed guide surface 5 to be traversed by the free portion of the switching member in moving from the on to the off positions and vice versa.

17. A switch comprising supporting means, an actuator in coöperative relation 10 with said supporting means, a switching member having an operative connection with the actuator, spring means between the actuator and the switching member, the supporting means having an insulating guide 15 surface to be traversed by the operative portion of the switching member between the on and off positions thereof.

18. The combination of supporting means having a guide surface, an actuator in coöperative relation with the supporting means, means governed by the actuator for 20 effecting snap movement of the switching

member to on and off positions, the switching member in moving from one position to the other traversing said guide surface, and 25 stops to arrest the switching member in predetermined extreme positions thereof.

19. A switch comprising supporting means, an actuator in coöperative relation with the supporting means, a switching 30 member associated with the actuator, spring means coacting with the actuator and the switching member, the actuator on its movements being adapted to condition the spring means to shift the switching member, and 35 the supporting means having a guide surface for the passage of the operative portion of the switching member.

In testimony whereof I affix my signature in the presence of two witnesses.
